SHEET HANDLING APPARATUS

Lewis Jones, Youngstown, Ohio

Application May 12, 1936, Serial No. 79,319

19 Claims. (Cl. 271—12)

This invention relates to apparatus for handling metal sheets, and more particularly to an apparatus for lifting and transferring single sheets from a sheet pack to a feed table or the like for the performance of any desired operations on the sheets.

At present, considerable difficulty is experienced in handling the large sheets of sheet packs due to the weight and size of the sheet, the sheets commonly being handled by hand. In such handling of the sheets it is extremely difficult to prevent the scratching and marring of the finished surfaces of the sheets, and the surface imperfections thus caused are visible on the finished articles into which the sheets are made.

An important object of the present invention is to provide a novel sheet handling apparatus for lifting single sheets from a pack and transferring them to a feed table or any other desired point.

A further object is to provide a novel apparatus of the character referred to wherein the sheet is lifted from the pack and supported on freely rotatable rollers to permit the sheet to be moved without marring either surface thereof.

A further object is to provide novel means for lifting one edge of a sheet to permit movement of the supporting rollers into position beneath the sheet.

A further object is to provide novel means for effecting movement of the sheet while it is supported on the rollers.

A further object is to provide novel means for effecting the successive operations of the apparatus, namely, the lifting of one edge of the sheet, the movement of the supporting rollers beneath the sheet, and the movement of the sheet to the desired point while it is supported on the rollers.

A further object is to provide a novel vacuum cup mechanism for lifting one edge of a sheet from a pack to facilitate the movement of the supporting rollers beneath the sheet, and to provide means for opening the vacuum cups to the atmosphere to release the sheet to permit free movement thereof on the supporting rollers.

Other objects and advantages of the invention will become apparent during the course of the following description.

In the drawings I have shown one embodiment of the invention. In this showing:

Figure 1 is a plan view of the apparatus,

Figure 2 is a detail vertical sectional view on line 2—2 of Figure 1,

Figure 3 is a detail horizontal sectional view on line 3—3 of Figure 2,

Figure 4 is a vertical longitudinal sectional view on line 4—4 of Figure 1,

Figure 5 is a transverse vertical sectional view on line 5—5 of Figure 4,

Figure 6 is a similar view on line 6—6 of Figure 4, and,

Figure 7 is a diagrammatic representation of an electrical system adapted for use in connection with the apparatus.

Referring to the drawings, the numeral 10 designates a pair of vertical parallel side frame members forming the main supporting means for the apparatus. Adjacent their ends, the side frames rotatably support a pair of shafts 11 and 12 each provided with a pair of sprockets indicated respectively by the numerals 13 and 14. A pair of chains 15 pass around the pairs of sprockets, as clearly shown in Figures 1 and 4.

The chains 15 have certain links thereof provided with projecting bearing lugs 16 and each opposite pair of lugs 16 supports a shaft 17, as shown in Figure 5. Each of these shafts is provided between the chains 15 with a supporting roller 18 freely rotatable with respect to the shaft by means of anti-friction bearings 19. Each shaft 17 carries a roller 20 at each end thereof, and each roller 20 is supported for free rotation by an anti-friction bearing 21. The side frame members 10 are provided at their upper and lower edges with flanges 22 over which the rollers 20 travel to support the upper and lower runs of the chain 15 between the pairs of sprockets. The flanges 22 preferably extend between and terminate at the vertical planes of the shafts 11 and 12.

Referring to Figures 1 and 5, the numeral 23 indicates a motor which is employed for driving the chains 15. This motor may be mounted on a suitable bracket 24 secured to one of the side frame members 10. The motor is provided with suitable speed reduction drive means for driving the shaft 12. In the present instance, the motor has been indicated as including a speed reduction unit 25 of conventional type.

As will become apparent, the rollers 18 are employed for supporting the upper sheet of a pack, and in Figure 4 a sheet pack 26 has been indicated as being supported by suitable cross members 27 and arranged between rails 28. The side frame members are provided with flanged wheels 29 adapted to travel on the rails 28, and accordingly it will be apparent that after a sheet pack has been placed in position between the rails, the apparatus as a whole may be moved along the rails to the position shown in Figure 4.

Means are provided for elevating one end of the uppermost sheet of the pack to permit the successive rollers 18 to travel beneath such sheet and support it for relatively frictionless movement over the rolls. Referring to Figures 2, 3 and 4, the numeral 30 designates a relatively heavy crossbar having a crosshead 31 at each end thereof mounted for vertical movement in suitable guides 32. The crossbar 30 is provided 10 with a pair of depending tubular members 33 at the lower end of each of which is secured a vacuum cup 34. Each tubular member 33 is provided above its associated vacuum cup with atmospheric openings 35. The lower end of each 15 tubular member is provided with a valve seat 36 normally engaged by a valve 37 urged upwardly to closed position by a spring 38. This spring surrounds a valve stem 39 which extends upwardly above the crossbar 30 through an opening 40 formed therein.

Above each valve stem 39 a solenoid 41 is supported on the crossbar 30 by a suitable bracket 42. Each solenoid 41 is provided with an armature 43 which has a depending non-magnetic 25 stem 44 adapted to engage the valve stem 39 to open the valve 37 upon energization of the solenoid. The purpose and operation of this mechanism will be referred to in detail later.

A shaft 45 extends transversely between the 30 side frame members and is suitably journaled at its ends therein. This shaft carries a pair of rocker arms 46 each of which is slotted at its end as at 47 to receive the crossbar 30. Accordingly it will be apparent that rocking movement of the arms 46 is adapted to effect vertical movement of the crossbar 30 and the elements 35 connected thereto.

An arm 48 is carried by the shaft 45 as shown 40 in Figures 1 and 4 and this arm is engaged by a cam 49 mounted upon a shaft 50 having its ends journaled in the side frame members. The high point 51 of the cam 49 normally supports the arms 46 in the position shown in Figure 4, and the throw of the cam is such that the low point 45 52 thereof will permit the arms 46 to move downwardly to a sufficient extent to permit the vacuum cups 34 to engage the lowermost sheet of the pack 26. The shaft 50 extends through one of the side frames 10 and is driven by a motor 53 through the medium of a conventional speed 50 reducing gearing 54.

Under conditions to be referred to, the successive rollers 18 move beneath the uppermost sheet of the pack after one end thereof has been 55 lifted by the vacuum cups 34 to the position shown in Figure 4. Means are provided for feeding from the apparatus the sheet supported upon the rollers 18 after they have been moved to the positions referred to. Referring to Figure 4 60 the numeral 55 designates a roller mounted upon a shaft 56 and covered by a relatively thick rubber or similar soft deformable jacket 57. The shaft 56 is connected adjacent the inner faces of the side frames 10 to one end of a pair of arms 65 58 having their other ends pivotally supported by a shaft 59. One end of the shaft 56 extends through one of the side frame members 10 and is provided with a sprocket 60. The side frame member 10 adjacent the sprocket 60 is provided 70 with an arcuate opening 61, as indicated in dotted lines in Figure 4, to permit a slight swinging movement of the arms 58. The opening 61 is concentric with the shaft 59, as will be apparent.

75 Each of the arms 58 is engageable with a

bracket 62 carried by the adjacent frame member 10 to limit the downward movement of these arms substantially to the position shown in Figure 4. A spring 63 urges each of the arms 58 downwardly, each spring engaging a spring seat 64 carried by the adjacent arm 58 and being seated at its upper end against a bracket 65 secured to the adjacent side frame member 10. It will be apparent that the springs 63 urge the rubber jacket 57 of the roller 55 into engagement 10 with a sheet supported upon the rollers 18 and the roller is positively driven to move the sheet toward the left as viewed in Figure 4. A chain 66 passes around the sprocket 60 and around a 15 sprocket 67 mounted on the shaft 59, as shown in Figure 1. A motor 68 drives the shaft 59 through a conventional speed reducing gearing 69.

Adjacent the left hand end of the apparatus, as viewed in Figures 1 and 4, a roller 70 is 20 mounted upon a shaft 71 and is rubber jacketed as at 72. This shaft is provided with a sprocket 73, as shown in Figure 1, and a chain 74 passes around this sprocket and around a sprocket 75 carried by the shaft 59. The sprockets 60 and 25 71 are equal in size respectively to the sprockets 73 and 75 and the circumference of the rubber jacket 57 is equal to that of the rubber jacket 72. The linear speeds of the rubber jacketed rollers referred to accordingly will be identical. 30 A second roller 76 is arranged beneath the roller 70 and is supported by a transverse shaft 77. This roller is likewise rubber jacketed as at 78, and the rubber jacketed rollers 70 and 76 accordingly act as pinch rolls to engage the sheet 35 and move it longitudinally from the apparatus.

The rubber jackets 72 and 78 may be thick 40 enough to permit them to be deformed to a sufficient extent to accommodate sheets of varying thicknesses. It is preferred however, that one of the pair of rollers be mounted so as to permit it to partake of slight movement away from the other roller. Accordingly the roller 70 is indicated as being supported by a pair of arms 79 pivotally connected to the side frame 45 members as at 80 and urged downwardly by springs 81 seating at their upper ends against brackets 82. The shaft 71 extends through an opening in the side frame member 10 adjacent the sprocket 72, this opening being slightly elongated similar to the opening 61 and arranged 50 concentric to the pivot axis of the arms 79. In view of the length of the chain 74 and the very slight movement of the roller 70, the chain 74 will not be unduly slackened or tightened upon 55 movement of the roller 70.

The apparatus may be provided with guides to insure the entrance of the advancing edge of a sheet between the rubber jacketed rollers 70 and 76. Referring to Figures 4 and 6 the 60 numeral 83 designates a pair of guides secured to the respective side frame members 10 and extending inwardly therefrom. These guide members curve upwardly toward the pinch rolls as shown in Figure 4. A pair of upper guides 84 65 may be similarly connected to the respective side frame members and arranged as shown in Figure 4, the two pairs of guides insuring the entrance of the advancing end of a sheet between the pinch rolls.

70 Suitable electric circuits are provided for the operating motors and other electrically operated parts of the apparatus to be described. These circuits include switches several of which are operated by the movement of the chains 15 and by 75

the upward movement of one of the sheets as it is elevated from the pack. In Figure 1 of the drawings two pivoted arms 85 and 86 are supported by the adjacent side frame members and constitute switch arms for closing circuits to be described. Each of these arms is provided with a roller 87 engageable with the uppermost sheet of the pack as it is elevated by the vacuum cups. These rollers are preferably formed of rubber to prevent any injury to the surface of the sheet. A similar switch arm 88 is arranged beyond the end of the apparatus as shown in Figures 1 and 4, and such switch arm also is provided with a rubber roller 89 adapted to contact with the successive sheets. A pair of switch arms also is adapted to be operated by one of the chains 15. As shown in Figure 4, a limit switch 90 is secured to one of the side frames and provided with a switch arm 91 engageable by a pin 92 (see Figure 5) carried by one of the chains 15. The switch arm 91 is arranged in a position to be operated when the pin 92 is in the lower run of the chain. A similar limit switch 93 is provided with a switch arm 94 likewise adapted to be operated by the pin 92 when the latter is in the upper run of the chain. Another switch 95 is carried by one of the side frame members and is provided with a depending pin 96 adapted to be operated by a cam 97 carried by the shaft 50.

30 An electrical system for the apparatus is illustrated diagrammatically in Figure 7 of the drawings. A pair of line wires 98 and 99 are connected to a suitable source of current. The wire 98 is connected to a push button switch 100 movable into engagement with a contact 101 to which is connected one end of a wire 102. Ahead of the switch 100, a wire 103 has one end connected to the line wire 98. A magnet switch is adapted to be operated upon the closing of the switch 100.

40 As shown, the magnet switch includes a magnet 104 having an armature 105 movable upwardly to engage a pair of contacts 106 and 107. The contact 101 is connected to one terminal of the magnet 104 by a wire 108, and a wire 109 is tapped into this wire and leads to the contact 106. The other terminal of the magnet 104 is connected by a wire 110 to one terminal of the motor 53.

The switch 95 includes a switch arm 111 operative by the stem 96. The switch arm 111 is respectively engageable with contacts 112 and 113, the latter being connected to the contact 107 as at 114. In the normal position of the parts, the cam 97 maintains the switch arm 111 in engagement with the contact 112, and upon initial rotation of the cam in a counter-clockwise direction, the stem 96 drops the switch arm 111 into engagement with the contact 113. The contact 112 is connected to one terminal of the motor 23 by a wire 115. Current is supplied to the switch arm 111 by a wire 116 tapped into the line wire 98. The motor 23 is not energized merely because the switch arm 111 is in engagement with the contact 112, the circuit to the motor 23 being completed only through other circuit elements to be described and controlling the passage of current through a wire 115' connected to the second terminal of the motor 23.

One terminal of the motor 68 is connected to 70 the line wire 98 by a wire 117 and the other terminal of this motor is connected by a wire 118 to one terminal of a magnet 119. The other terminal of this magnet is connected by a wire 120 to a common wire 121 connected at its ends to 75 the switch arms 86 and 88. These switches are

respectively movable into engagement with contacts 122 and 123 connected in parallel by a wire 124 and this wire also leads to a contact 125.

The switch arm 94 is biased to a position in engagement with a contact 126 connected to one end of a wire 127. The other end of this wire is connected to the switch arm 91. The switch arm 94 carries a switch element 128 insulated therefrom and engageable with the contact 125 and with a second contact 129. The latter contact 129 is connected to the line wire 99 as at 130. The switch arm 94 also carries a second switch element 131 insulated therefrom and connected to the wire 127 as at 132. The switch element 131 is movable into engagement with a contact 133 connected to one end of a wire 134.

The switch arm 94, as previously stated, is operated by movement of the chains 15 and normally engages the contact 126. A wire 135 connects the switch arm 94 to a contact 136 which is engageable by the switch arm 85, and this switch arm is connected to the line wire 99 as at 137.

A magnet 138 has one of its terminals connected to the wire 134. The other terminal of this magnet is connected by a wire 139 to the armature 140 of the magnet 119. The armature 140 constitutes a switch arm normally engaging a contact 141 connected by a wire 142 to the line wire 99.

30 The magnet 138 is provided with an armature 143 forming a switch arm movable upon energization of the magnet into engagement with a pair of contacts 144 and 145, the latter being connected as at 146 to the wire 134. The contact 144 is connected by a wire 147 to a contact 148. The switch arm 91 is biased toward engagement with the contact 148 and is held out of engagement with such contact in the starting position of the apparatus, as shown in Figure 7.

40 As will become apparent, the switch 100 may be closed to initiate the operation of the apparatus and to cause it to completely carry out its cycle of operation. Upon completion of the cycle of operation, the apparatus will then stop pending further manual operation of the switch 100. If desired, the apparatus may be provided with circuit means for causing it to continuously repeat its cycle of operation. The wires 103 and 102 are 45 employed for this purpose and are respectively connected to a contact 149 and to a switch element 150 carried by and insulated from the switch 91. A manually operable control switch 151 is arranged in the wire 103, as shown.

The windings of the magnets 41 are connected 50 in parallel by wires 152 and 153, these wires being shown as being connected to one of the magnets 41 while the other magnet has its terminals respectively connected with the two wires referred to, as at 154 and 155. The wires 152 and 153 55 are respectively connected to the wires 118 and 117 and accordingly the magnet circuits are in parallel with the circuit of the motor 68.

The operation of the apparatus is as follows: 60 The parts of the apparatus are initially in the position shown in Figure 4, the switch operating pin 92 being in the bottom of the run of this chain as shown in Figure 5, engaging the switch arm 91 and holding it in the position shown in Figure 7. A pack of sheets is placed in position 70 between the rails 28 adjacent a work table or similar apparatus to which the sheets are delivered. The present apparatus is then rolled along the rails to the position shown in Figure 4, whereupon the apparatus is ready for operation. 75

Disregarding the circuit including the wires 102 and 103 and assuming the switch 151 to be open, the circuit through the motor 53 will be broken since the switches 100 and 105 are open. Several circuits are provided for the motor 23, such circuits being closed under different conditions to be referred to, and all of these circuits are broken at one or more points in the starting position of the parts of the apparatus. For example, in the absence of a sheet engaging the roller 87, the switch 85 will be open, and the switch arm 91 is being held out of engagement with the contact 148. Likewise the circuit through the motor 68 is broken since the two switches 86 and 88 are both in open position.

The operation of the apparatus is initiated by closing the push button switch 100 and holding it closed for a few seconds. Upon the closing of this switch, the circuit through the motor 53 will be closed through the switch 100 and magnet 104, the latter being in series with the motor 53. This motor will start to run and will rotate the switch operating cam 97 and the cam 49 which controls the arms 46. Only a short interval of time is required for the high point of the cam 97 to pass from beneath the pin 96 whereupon the switch 111 drops into contact with the contact 113, the switch arm obviously moving out of engagement with the contact 112.

Energization of the magnet 104 will have attracted its armature 105, whereupon a holding circuit will be provided for the motor 53 through wire 116, switch 111, wire 114, contacts 106 and 107 and wire 109. Immediately upon the dropping of the switch arm 111, therefore, the push button switch 100 may be released and the motor 53 will continue to operate.

The motor 53 rotates the cam 49 and the high point of this cam passes from beneath the arm 48, thus permitting the arms 46 to move downwardly. Such movement of the arms 46 is permitted to take place freely until the vacuum cups 34 engage the upper sheet of the pack and the weights of the arms 46, cross bar 30, etc., combine to provide sufficient downward force to expel a substantial amount of air from the vacuum cups 34. This expulsion of air causes the creation of a sufficient vacuum upon the subsequent lifting of the arms 46 to cause the vacuum cups 50 to pick up the adjacent end of the upper sheet, as shown in Figure 4.

After downward movement of the arms 46 is stopped by contact of the vacuum cups with the top sheet of the pack, the cam 49 will continue to revolve and, of course, will move out of contact with the arm 48. As previously stated, the throw of the cam 49 is sufficient to permit the arms 46 to move downwardly the necessary distance in order that the vacuum cups may engage the lowermost sheet of the pack after all of the remaining sheets have been removed. Upon the continued operation of the cam 49, this cam will engage the arm 48 and move it upwardly, the vacuum cups elevating the adjacent 65 end of the sheet in the manner previously stated.

The arms 46 are moved upwardly to their normal position, as shown in Figure 4, at which time the cam 97 will operate the switch 111 to disconnect it from the contact 113 and move it 70 into engagement with the contact 112. The holding circuit for the magnet 104 thereupon will be broken, the motor 53 stopping, while the armature 105 drops to its normal position as shown in Figure 7.

While the switch 111 was in its lower position

out of engagement with the contact 112, the vacuum cups will have been operating to lift the upper sheet of the pack, and the elevated portion of the sheet will contact with the rollers of both of the switch arms 85 and 86, thus moving these switch arms into engagement with their respective contacts 136 and 122. When the vacuum cups reach their upper position and the switch arm engages the contact 112, a circuit will be established, therefore, through the motor 23, the circuit including wires 115' and 127, contact 126 and switch arm 94, wire 135, contact 136, switch arm 85 and wire 137.

As the motor 53 ceases to operate, therefore, the motor 23 will commence to operate to drive 15 the chains 15 in the direction of the arrow shown in Figure 4. The advancing roller 18 will pass beneath the elevated portion of the upper sheet of the pack and will continue to move beneath such sheet to progressively elevate it from the 20 left hand end of the sheet to the right hand end thereof as viewed in Figure 4. The successive rollers 18 will pass beneath the sheet and thus the latter will be effectively supported. Initial operation of the chains 15 from the position 25 shown in Figure 7 will have caused the pin 92 to release the switch 91 to permit the latter to move into engagement with the contact 148. No circuit will be closed under such conditions, however, since the circuit including the contact 30 148 will be broken across the contacts 144 and 145.

The chains will continue to operate until the rollers 18 are all positioned beneath the top sheet of the pack and when this position is reached, 35 the switch operating pin 92 will engage the switch arm 94 to move it out of engagement with its contact 126. At the same time the switch element 131 will engage the contact 133, while the switch element 128 will engage the contacts 125 40 and 129. The previously described circuit of the motor 23 thereupon will be broken at the contact 126, and accordingly this motor will be de-energized and the chains 15 will stop with the pin 92 holding the switch arm 94 in the position just described. 45

At the instant the switch arm 94 swings to the position in which the switch element 131 engages the contact 133, a circuit will be apparently momentarily completed through the motor 23, such circuit including the switch element 131, 50 contact 133, wire 134, magnet 138, wire 139, armature 140 and wire 142. At the instant of the closing of such circuit, however, the circuit will be closed through the motor 68, through wires 55 117 and 118, magnet 119, wires 120 and 121, switch 86 (such switch having been closed upon initial elevation of the sheet) wire 124, contact 125, switch element 128, contact 129 and wire 130. This circuit includes the magnet 119, and 60 at the instant the circuit is completed through the armature 140, the magnet 119 will attract this armature and will hold it out of engagement with the contact 141 throughout the operation of the motor 68. The movement of the switch arm 65 94 by the pin 92, therefore, will break the previous circuit through the motor 23 at the contact 126 and will prevent the reclosing of a circuit through this motor by opening the switch 140.

Accordingly the motor 23 will go out of operation when all of the rollers 18 are positioned beneath the top sheet, and the motor 68 will operate to remove the sheet as it stands upon the rollers. Moreover, at the instant the circuit through the motor 68 is completed, air is ad- 75

mitted into the vacuum cups 34 to release the elevated sheet. It will be noted that the circuits of the solenoids 41 are in parallel with each other and with the motor 68. At the instant this 5 motor is energized, therefore, the armatures 43 of the solenoids 41 will be moved downwardly and the stems 44 will engage the valve stems 39, whereupon the valves 37 will open to connect the vacuum cups to the atmosphere through ports 10 35. Thus the vacuum cup will release the sheet and it will be supported upon the freely rotatable rollers 18.

In this connection it will be noted that the frictional resistance to the turning movement of 15 the rollers is reduced to a minimum by the use of the bearings which support the rollers on the shafts 17, and that resistance to the movement of the rollers 20 is reduced by the mounting of these rollers on the shafts 17. In the operation 20 of the apparatus the rollers 18 and 20 rotate in opposite directions, and such operation is permitted freely to take place with the arrangement referred to.

The motor 68 drives the shaft 59, and this 25 shaft in turn drives the shafts 56 and 71. When the rollers 18 are arranged in position beneath a sheet to support it above the pack, one of the rollers 18 will be arranged directly beneath the rubber jacketed roller 55, thus supporting the sheet against this roller, and rotation thereof will start the sheet moving to the left as viewed in Figure 4. The advancing edge of the sheet will pass between the rubber jacketed pinch rolls 30 70 and 76 and the former of these two rollers, being positively driven, will continue the ejection 35 of the sheet from the apparatus. The sheet will be thus completely moved out of the apparatus to a feed table or the like ready for the performance of subsequent operations on the 40 sheet.

It will be apparent that the switches 86 and 45 88 are connected in parallel, and either or both of these switches will maintain the circuit through the motor 68 closed so long as the switch element 128 is in engagement with the contacts 125 and 129. The switch arm 86 is elevated upon the initial raising of one end of the sheet by the 50 vacuum cups and is held in upper position by the sheet until the right hand end of the sheet, as viewed in Figure 4, passes from beneath this switch arm. In the meantime, however, the advancing end of the sheet will have elevated the switch arm 88 into engagement with the contact 123, and the dropping of the arm 86 following 55 the passing of the sheet therebeyond will not affect the circuit through the motor 68. However, the passing of the sheet completely from the apparatus will permit the arm 88 to drop and move out of engagement with the contact 123, 60 and both parallel circuits for the motor 68 thus will be broken and the motor will promptly stop.

Since the circuit for the motor 68 includes the 65 magnet 119, deenergization of the motor circuit will drop the armature 140 into engagement with the contact 141. This action again energizes the motor 23, which drives the chains 15, the circuit from the motor 23 under such conditions including wires 115, 115', 127 and 132, switch element 131 and contact 133, wire 134, magnet 138, 70 armature 140 and wire 142. Accordingly the motor 123 will again start to operate, and it will be recalled that the chains will have been previously stopped with the pin 92 holding the switch arm 94 out of engagement with the contact 126 and 75 with the switch element 131 in engagement with

the contact 133. Upon relatively slight movement of the chains, the pin 92 will release the switch arm 94 for return movement to the normal position shown in Figure 7, but this movement does not affect the operation of the motor 23. Under 5 the conditions being considered, the switch arm 91 will be in engagement with the contact 148 and immediately upon the energization of the magnet 138 in the manner previously described, a parallel holding circuit will be provided for the 10 motor 23, such circuit including wires 115' and 127, switch 91 and contact 148, wire 147, contact 144, armature 143, contact 145, wire 146, and thence back to the source through the formerly completed path comprising the magnet 138, wire 15 139, etc. Accordingly it will be apparent that upon energization of the magnet 138, a second and parallel circuit is closed through this magnet to provide a holding circuit for the motor 23. This circuit is maintained closed until the parts 20 are restored to the normal position shown in Figure 4, at which point the pin 92 will again engage the arm 91 to move it out of engagement with the contact 148. Both circuits for the magnet 138 will then be broken and the armature 25 143 will drop to the normal position shown in Figure 7. All three motors will now be deenergized and all of the parts will be in their original starting positions.

From the foregoing it will be apparent that 30 the complete cycle of operation may be carried out merely by momentarily closing the switch 100, all of the successive functions of the apparatus being properly timed and automatically carried out to the completion of the cycle of operation. 35 When the latter point is reached all of the parts are in the proper initial starting positions, whereupon the next cycle of operation may be initiated by momentarily closing the switch 100. If desired, successive operations may be auto- 40 matically performed without any manual control by the operator, and such operation is provided merely by closing the switch 151 and leaving it in closed position. This switch controls a circuit which is in parallel with the push button switch 100 and is dependent for its closing upon the presence of the switch operating pin 92 in its starting position shown in Figure 7. In other words, when a cycle of operation is completed the pin 92 returns to the position 50 shown in Figure 7 and moves the switch arm 91 to bring the switch element 150 into engagement with the contact 149, thus closing a shunt circuit around the push button switch 100 to initiate the operation of the apparatus. The pin 92 will not release the limit switch 91 until after the switch stem 96 has dropped from the high point of the cam 97, which operation provides a holding circuit for the motor 53 to cause the latter to complete its operation in the manner 55 previously described. After such holding circuit is closed, the switch 91 returns to its normal position and remains in such position until the entire cycle of operation of the apparatus has been completed.

The present apparatus therefore provides mechanical means for handling the finished sheets of a pack to prevent them from being marred or scratched, thus preventing the spoiling of the finished articles made from the sheet. The vacuum cups 34, the coverings of the rollers 55, 70 75 and 76 and the rollers of the switches 85, 86 and 88 are all formed of rubber or other soft material and these elements contact with the sheet without any sliding contact which would mar the sheet, 75

and accordingly the sheets are delivered to the feed table in perfect and undamaged condition.

It is to be understood that the form of the invention herewith shown and described is to be taken as a preferred example of the same and that various changes in the shape, size and arrangement of parts may be resorted to without departing from the spirit of the invention or the scope of the subjoined claims.

10 I claim:

1. A sheet handling apparatus comprising means engageable with an end portion of a sheet to elevate it, supporting means movable horizontally beneath the sheet from the elevated end thereof, a feed roll arranged with its lower extremity approximately at the plane of the upper surface of a sheet supported on said supporting means and engaging the sheet, and means for rotating said feed roll.

20 2. A sheet handling apparatus comprising means engageable with an end portion of a sheet to elevate it, supporting means movable horizontally beneath the sheet from the elevated end thereof, a feed roll arranged with its lower extremity approximately at the plane of the upper surface of a sheet supported on said supporting means and engaging the sheet, a pair of pinch rolls engageable with the advancing edge of the sheet, and means for rotating said feed roll and said pinch rolls at equal peripheral speeds.

30 3. A sheet handling apparatus comprising means engageable with an end portion of a sheet to elevate it, a plurality of freely rotatable supporting rollers connected together for bodily movement in parallel relationship, means for moving said rollers beneath the sheet from the elevated end thereof, and means actuatable independently of said last named means for effecting horizontal movement of the sheet supported on said rollers.

40 4. A sheet handling apparatus comprising means engageable with an end portion of a sheet to elevate it, a plurality of freely rotatable supporting rollers connected together for bodily movement in parallel relationship, means for moving said rollers beneath the sheet from the elevated end thereof, and feed roll means engageable with the sheet supported on said rollers for effecting horizontal movement of the sheet.

50 5. A sheet handling apparatus comprising means engageable with an end portion of a sheet to elevate it, a plurality of freely rotatable supporting rollers connected together for bodily movement in parallel relationship, means for moving said rollers beneath the sheet from the elevated end thereof, a feed roll having its bottom extremity arranged approximately in the plane of the upper surface of a sheet supported on said rollers and engageable with the sheet, and means for rotating said feed roll.

60 6. A sheet handling apparatus comprising means engageable with an end portion of a sheet to elevate it, a plurality of freely rotatable supporting rollers connected together for bodily movement in parallel relationship, means for moving said rollers beneath the sheet from the elevated end thereof, a feed roll having its bottom extremity arranged approximately in the plane of the upper surface of a sheet supported on said rollers and engageable with the sheet, means for rotating said feed roll to effect horizontal movement of the sheet, a pair of pinch rolls engageable with the advancing edge of the

sheet, and means for rotating said pinch rolls at the same peripheral speed as said feed roll.

7. A sheet handling apparatus comprising vacuum cup means movable downwardly into engagement with the upper surface of a sheet adjacent one end portion thereof and then upwardly to elevate such end portion of the sheet, supporting means movable beneath the sheet from the elevated end thereof, means for releasing said vacuum cup means from the sheet after the latter is supported by said supporting means, a feed roll having its bottom extremity arranged approximately in the plane of the upper surface of a sheet supported by said supporting means, and means for rotating said feed roll.

15 8. A sheet handling apparatus comprising vacuum cup means movable downwardly into engagement with the upper surface of a sheet adjacent one end portion thereof and then upwardly to elevate such end portion of the sheet, supporting means movable beneath the sheet from the elevated end thereof, means for releasing said vacuum cup means from the sheet after the latter is supported by said supporting means, a feed roll having its bottom extremity arranged approximately in the plane of the upper surface of a sheet supported by said supporting means, means for rotating said feed roll to effect horizontal movement of the sheet, a pair of pinch rolls arranged in the path of movement of the sheet and engageable with the advancing edge thereof, and means for rotating said pinch rolls at the same peripheral speed as said feed roll.

25 9. A sheet handling apparatus comprising vacuum cup means movable downwardly into engagement with the upper surface of a sheet adjacent one end portion thereof and then upwardly to elevate such end portion of the sheet, a plurality of supporting rollers connected for bodily movement in parallel relationship and movable to a position beneath the sheet from the elevated end thereof, means for releasing said vacuum cup means from the sheet after said rollers have moved therebeneath, a feed roll arranged with its bottom extremity approximately in the plane of the upper surface of the sheet supported on said rollers and arranged parallel to the latter, and means for rotating said feed roll.

35 10. A sheet handling apparatus comprising vacuum cup means movable downwardly into engagement with the upper surface of a sheet adjacent one end portion thereof and then upwardly to elevate such end portion of the sheet, a plurality of supporting rollers connected for bodily movement in parallel relationship and movable to a position beneath the sheet from the elevated end thereof, means for releasing said vacuum cup means from the sheet after said rollers have moved therebeneath, a feed roll arranged with its bottom extremity approximately in the plane of the upper surface of the sheet supported on said rollers and arranged parallel to the latter, means for rotating said feed roll to effect horizontal movement of the sheet, a pair of pinch rolls arranged parallel to said feed roll and engageable with the advancing edge of the sheet, and means for rotating said pinch rolls at the same peripheral speed as said feed roll.

45 11. A sheet handling apparatus comprising a vacuum cup, means for effecting a cycle of operation of said cup downwardly from a normal position into engagement with the upper surface of a sheet adjacent one end portion thereof and

- then upwardly to such normal position to elevate such end portion of the sheet, a plurality of supporting rollers connected together for bodily parallel movement, means for effecting movement of said rollers to positions beneath the sheet from the elevated end thereof, means for releasing said vacuum cup from the sheet when said rollers are arranged therebeneath, and a feed roll having its bottom extremity arranged approximately in the plane of the upper surface of a sheet supported on said rollers and engageable with the sheet, and means for rotating said feed roll.
12. A sheet handling apparatus comprising a vacuum cup, means for effecting a cycle of operation of said cup downwardly from a normal position into engagement with the upper surface of a sheet adjacent one end portion thereof and then upwardly to such normal position to elevate such end portion of the sheet, a plurality of supporting rollers connected together for bodily parallel movement, means for effecting movement of said rollers to positions beneath the sheet from the elevated end thereof, means for releasing said vacuum cup from the sheet when said rollers are arranged therebeneath, a feed roll arranged parallel to said supporting rollers and engageable with the upper surface of a sheet supported thereon and operative for moving the sheet horizontally, a pair of pinch rolls arranged parallel to said feed roll and engageable with the advancing edge of the sheet, and means for rotating said feed roll and said pinch rolls at equal peripheral speeds.
13. A sheet handling apparatus comprising means engageable with an end portion of a sheet to elevate said end portion, a plurality of freely rotatable supporting rollers connected together for bodily movement in parallel relationship, means for moving said rollers beneath the sheet from the elevated end thereof to an operative position effecting complete elevation of said sheet, means for effecting removal of said sheet from the supporting rollers, and holding means for preventing movement of the supporting rollers from operative position until after removal of the sheet from said supporting rollers has been effected.
14. A sheet handling apparatus comprising means engageable with an end portion of a sheet to elevate said end portion, a plurality of freely rotatable supporting rollers connected together for bodily movement in parallel relationship, means for moving said rollers beneath the sheet from the elevated end thereof to an operative position for effecting complete elevation of said sheet, means for effecting removal of said sheet from the supporting rollers, holding means for preventing movement of the supporting rollers from operative position until after removal of the sheet from said supporting rollers has been effected, and means automatically operative thereafter for returning said supporting rollers to their initial position.
15. A sheet handling apparatus comprising a pair of spaced endless members having upper and lower runs, a plurality of rollers supported in spaced parallel relationship by said endless members and freely rotatable on their axes, means for supporting a pack of sheets beneath the lower runs of said endless members, means for elevating one end of the upper sheet of the pack, means for operating said endless members to move said rollers from the upper runs of said endless members to the lower runs thereof beneath the elevated end of said sheet, and means actuable independently of said last named means for imparting movement to said sheet supported on said rollers to remove it therefrom.
16. A sheet handling apparatus comprising a pair of spaced endless members having upper and lower runs, a plurality of rollers supported in spaced parallel relationship by said endless members and freely rotatable on their axes, means for supporting a pack of sheets beneath the lower runs of said endless members, means for elevating one end of the upper sheet of the pack, means for operating said endless members to move said rollers from the upper runs of said endless members to the lower runs thereof beneath the elevated end of said sheet, automatic means for releasing said elevating means from said sheet when said rollers are moved entirely beneath said sheet, and means independent of said operating means and engageable with the sheet after said elevating means is released therefrom for effecting movement of the sheet from said rollers.
17. A sheet handling apparatus comprising means engageable with an end portion of a sheet to elevate it, supporting means movable horizontally from the elevated end of the sheet to an operative position beneath the sheet, means for effecting movement of said supporting means to such operative position, means for stopping the movement of said supporting means in its operative position, and means engageable with the sheet while said supporting means remains in its operative position for effecting horizontal movement of the sheet from said supporting means.
18. A sheet handling apparatus comprising means engageable with an end portion of a sheet to elevate it, supporting means bodily movable horizontally from the elevated end of the sheet to an operative position beneath the sheet to support the latter, and means engageable with the sheet for moving the latter from said supporting means independently of bodily movement thereof.
19. A sheet handling apparatus comprising means engageable with an end portion of a sheet to elevate it, a plurality of freely rotatable supporting rollers connected for bodily movement in parallel relationship, means for bodily moving said rollers from the elevated end of the sheet to operative position beneath the sheet for supporting the latter, means for rendering said last named means inoperative when said rollers reach operative position, and means rendered operative upon operation of said last named means for effecting horizontal movement of the sheet from said supporting rollers.

LEWIS JONES.
